(57) **CLAIM**

The ornamental design for a cat scratcher, as shown and described.

DESCRIPTION

FIG. 1 is a perspective view of a first embodiment of the cat scratcher showing my new design.

FIG. 2 is a front elevation view thereof.

FIG. 3 is a right side elevation view thereof.

FIG. 4 is a rear elevation view thereof.

FIG. 5 is a left side elevation view thereof.

FIG. 6 is a top plan view thereof.

FIG. 7 is a bottom view thereof.

FIG. 8 is a perspective view of a second embodiment of the cat scratcher showing my new design.

FIG. 9 is a front elevation view thereof.

FIG. 10 is a right side elevation view thereof.

FIG. 11 is a rear elevation view thereof.

FIG. 12 is a left side elevation view thereof.

FIG. 13 is a top plan view thereof; and,

FIG. 14 is a bottom view thereof.

The broken lines in FIGS. 1-7 show portions of the cat scratcher that form no part of the claimed design. The broken lines in FIGS. 8-14 illustrate environmental structure that form no part of the claimed design.

1 Claim, 12 Drawing Sheets
